UNITED STATES PATENT OFFICE.

MALCOLM W. EDGAR, OF DETROIT, MICHIGAN, ASSIGNOR OF ONE-HALF TO
JAMES MCGREGOR, OF SAME PLACE.

RAILWAY-CAR.

SPECIFICATION forming part of Letters Patent No. 509,300, dated November 21, 1893.

Application filed October 26, 1892. Serial No. 450,050. (No model.)

To all whom it may concern:

Be it known that I, MALCOLM W. EDGAR, a citizen of the United States, residing at Detroit, in the county of Wayne and State of Michigan, have invented certain new and useful Improvements in Railway-Cars, of which the following is a specification, reference being had therein to the accompanying drawings.

10 The invention consists in the peculiar construction of a metallic frame; further in the peculiar construction of the plates and the means for securing the roofing boards in position; further in the peculiar construction, arrangement and combination of the various parts.

In the drawings, Figure 1 is a top plan view of the platform. Fig. 2 is a sectional elevation of the car frame. Fig. 3 is an end elevation of the car partly in section. Fig. 4 is 20 an enlarged sectional elevation of a part of Fig. 3, showing the manner of securing the upper ends of the siding and the roofing boards. Fig. 5 is an elevation of one of the transoms. Fig. 6 is a horizontal section illustrating the manner of securing the ends of the diagonal brace rods, the tie rods and spacing sleeves. Fig. 7 is a vertical section through the two center sills, showing the rod in elevation.

30 The frame of the car consists of the two longitudinal side sills A A' on each side of the center of the car, and two center sills B. The side sills are flanged beams, presenting an outwardly opening channel, preferably I-beams. The central sills are preferably channel beams with their flanges extending outwardly and are of a considerable greater depth than the side sills.

The central sills are separated to allow of 40 securing a suitable draft rig C between their inner faces, at the ends. The central beams have the end extensions C' at each end, formed by cutting out a rectangular section from their upper faces, of a depth equal to the depth of the side sills.

D are end beams of channel iron having the channel extending outwardly, and secured to the ends of the sills by suitable angle plates, or in any other known manner.

45 E are tie rods (see Figs. 1, 6 and 7) passing

through apertures in the webs of the sills, from side to side.

E' are spacing sleeves, preferably consisting of pipe sleeved over the tie rods, in sections of a length to bear at each end against the webs of the sills and be tightly clamped between as shown in detail in Fig. 7.

F are tie plates, resting upon the upper flanges of the sills (which are arranged in line) and riveted thereto, extending from edge to edge.

G are truss plates preferably in the form of I beams having their upper flanges riveted to the lower flanges of the side sills and extending from the outer edge of the frame to the outer faces of the central sills, as shown in Fig. 3. At their inner ends they are secured by angle plates G' or in any other suitable manner to the outer faces of the central sills.

H are bottom tie plates connecting the lower edges of the central sills, being riveted to the lower flanges thereof and preferably having the upwardly extending hook H' engaging the outer edges of the flanges of the sill.

I are the truss posts having at their lower ends a pin J about which the truss rods K are formed in coils K', as shown in Fig. 3, a suitable key K² being passed through the pin beneath to prevent any possible disengagement of the truss rods from the pin. The truss rods pass up over the transoms and are secured to the end beams in the usual manner.

The transom consists of the upper member L passing from side to side of the car, over the top of the central sill and the side sills A', but at its outer ends bent down sufficiently to pass beneath the inner flanges of the sills A and provided with the bent end L', adapted to fit against the web of the side sill A, being riveted or bolted thereto, the lower member M passing beneath the central sills and the intermediate sills A', as shown in Fig. 5, and abuts with its outer ends against the bent end L' of the upper member, being secured to the horizontal portion of the upper member.

M' are suitable transom filling blocks beside the sills, and secured thereto.

I desire to arrange diagonal braces from

centrally of the ends of the car to the outside middle portions thereof and also to arrange these braces without making apertures in the sills through which to pass them. To accomplish this, I make the braces in sections; as all of the braces are alike a description of one will suffice.

The brace consists of the section *a* extending from the outer face of the central sill diagonally to the inner face of the side sill *A'*. At its end it is provided with an eye *b*, as shown in Fig. 6, bent at an angle to the brace so that it will lie flush against the side of the web of the side sill, and the tie rods *E* pass through that eye while the spacing sleeves *E'* clamp it tightly against the web. The next section of the brace rod *c* is correspondingly formed with an eye on the opposite side of the web of the sill *A'* sleeved over the tie rod and clamped by the spacing sleeve, and extends diagonally to the center of the car where it is provided with a corresponding eye, engaging the central tie rod, upon the inner face of the outside sill *A*, as plainly shown in Fig. 1. Each section of the brace rod is provided with a suitable turnbuckle *d* so that necessary tension may be put thereon. These diagonal brace rods, extending the entire length of the car will brace the car against any lateral bending under any strain.

A metallic frame thus constructed gives me a maximum of strength with a minimum of weight.

From the description previously given, it will be seen that the side and end beams form an outwardly opening channel extending entirely around the car, and in this channel are secured filler blocks *O* of wood extending out flush with, or slightly beyond the outer faces of the flanges of these beams, forming a means for nailing or otherwise securing the siding *O'* thereto.

Upon the top of the side and end sills and riveted to the upper flanges thereof are secured suitable posts and brace shoes *P* in which the posts and braces *P'* and *P''* are respectively engaged, the upper ends of which engage corresponding shoes *Q* which are secured to the lower flanges of the channel beams *R* forming the plates. These channel beams are arranged with the channel opening outwardly and filled with a suitable wooden filler *R'*, as shown in Fig. 4. The siding is secured at its upper ends to this filler in the same manner as it is secured to the filler at the lower end.

S are metallic sockets secured to the inner faces of the plates in which the ends of the carlings *S'* rest. The plates are tied together by suitable tie rods and suitable roofing boards *T* are secured upon the carlings, projecting at their inner ends over the plates and secured at their ends to a cornice or molding strip *T'* which is secured at the top of the siding, as shown in Figs. 3 and 5.

A car of this construction being a composite metal and wooden car enables me to em-

ploy metallic beams for all the sills and plates where long beams are required and to use short stuff for the posts, braces and roofing 70 timbers.

To secure the floor in position I bolt to the upper faces of the sills suitable flooring strips *U* upon which the flooring is secured, as shown in Fig. 3.

What I claim as my invention is—

1. In a composite wood and metal car, the combination with sills of channeled iron, of wood filler in the outer faces of the sills, channeled plates at the top of the car having 80 wood filling in their outer faces and sidings secured to the wood fillings, at top and bottom, substantially as described.

2. In a composite wood and metal car, the combination with longitudinal sills formed 85 of channeled iron having an outer filling of wood, of a series of metal sockets secured on the top of the sills at intervals, brace posts having their lower ends in the sockets and a siding secured to the filling, substantially as 90 described.

3. In a composite metal and wooden car, a roof frame comprising metallic plates, shoes on their inner faces, carlings having their 95 ends resting in said shoes, a wooden strip outside the plates, and roof boards overlapping said strip and secured thereto, substantially as described.

4. In a composite metal and wooden car the combination of plates of metal, having an outwardly opening channel, a wooden filler therein, the siding secured to said filler, molding or cornice strips at the upper end of the siding, the roof frame, and the roof boards overlapping the cornice and secured thereto, substantially as described.

5. In a railway car, a metallic frame comprising side sills, central sills of greater depth than the side sills, all arranged with their upper faces in line, tie rods passing through all the sills and separating sleeves upon the rods between the sills, substantially as described.

6. In a railway car, a metallic frame comprising side sills and central sills of greater depth than the side sills, all arranged with 115 their upper faces in line, tie rods passing through all the sills, separating sleeves upon the rods between the sills, substantially as described.

7. In a railway car, a metallic frame comprising flanged side and central sills, the central sills being of greater depth than the side sills, all arranged with the upper faces in line, tie rods passing through all the sills, tie plates 125 riveted to the tops of all the sills, bottom tie plates connecting the central sill only, and end channel beams connecting the sills, substantially as described.

8. In a railway car, the combination of 130 flanged side and central sills arranged with their upper faces in line, the central sills being of greater depth than the side sills, of flanged truss plates secured on the under sides

of the side sills abutting against and secured at their inner ends to the central sills, truss posts depending from said plates, and the longitudinal truss rods, substantially as described.

5 9. In a railway car frame, the combination of the longitudinal sills and cross-ties, of the side and end sills having outwardly opening channels, a wooden filler in said channels extending entirely around the car, and the sides secured to said filler, substantially as described.

10. In a railway car, the combination of a frame having longitudinal sills, of diagonal braces extending from centrally of the ends of the car to the sides, substantially as described.

15 11. In a railway car, the combination of a frame having longitudinal sills, of diagonal braces made in sections extending diagonally between the adjacent sills having their ends connected on opposite sides thereof, substantially as described.

20 12. In a railway car the combination of a

frame having longitudinal metal sills, of tie rods, spacing sleeves between the sills through which the rods pass, and diagonal brace rods made in sections extending diagonally between the sills, having eyes at their ends through which the tie rods pass, substantially as described.

25 13. In a railway car, the combination of the frame, the truss rods and the truss posts having a pin at the lower end around which the truss rods are turned, substantially as described.

30 14. In a railway car, the combination of the frame, the truss rods, the truss posts having a pin at the lower end, a coil in the truss rods around said pin and a key through the pin below the coil, substantially as described.

35 In testimony whereof I affix my signature in presence of two witnesses.

MALCOLM W. EDGAR.
